UNITED STATES PATENT OFFICE

119,429

DESIGN FOR A MOTOR DRIVEN SHAVER

John Nelson Frey, Union Township, Union County, N. J., assignor, by mesne assignments, to Samuel Gorad, New York, N. Y.

Application July 14, 1939, Serial No. 86,013

Term of patent 14 years

To all whom it may concern:

Be it known that I, John Nelson Frey, a citizen of the United States and resident of the township of Union, in the county of Union and State of New Jersey, have invented a new, original, and ornamental Design for a Motor Driven Shaver, of which the following is a specification, reference being had to the accompanying drawing, forming part thereof.

Figure 1 is a top plan view of a motor driven shaver showing my new design.

Figure 2 is a front elevation thereof.

Figure 3 is a side elevation thereof.

Figure 4 is a section along the line 4—4 of Figure 3.

The side of the motor driven shaver opposite the side elevation shown in Figure 3 presents substantially the same appearance as the side shown.

The dominant feature of the design resides in the portion shown in full lines in the drawing.

I claim:

The ornamental design for a motor driven shaver, substantially as shown and described.

JOHN NELSON FREY.
